UNITED STATES PATENT OFFICE.

JULIUS W. LANDQUIST, OF WOODLAND, CALIFORNIA.

GARMENT-SUPPORT.

1,278,945.

Specification of Letters Patent. Patented Sept. 17, 1918.

Application filed June 28, 1916. Serial No. 106,452.

To all whom it may concern:

Be it known that I, JULIUS W. LANDQUIST, a citizen of the United States, residing at Woodland, in the county of Yolo and State 5 of California, have invented certain new and useful Improvements in Garment-Supports, of which the following is a specification.

This invention relates generally to garment supporting devices, and has particular 10 reference to improved means for supporting under body garments.

The primary object of the invention is to provide a simplified device, by the use of which the drawer garment may be held with 15 a trouser or other outer apparel in such manner as to insure perfect hanging of the undergarment, as well as comfort to the wearer, and to enable the drawer garment to be readily detached when desired.

20 A further object of the invention is to provide a supporting device of the character mentioned which is of exceedingly simple and inexpensive construction, which constitutes a part of or is permanently secured to 25 the outer garment, which does not detract from the appearance of the outer garment, which positively prevents the under garment from falling or slipping out of proper position, and which is capable of being readily 30 manipulated to release the undergarment.

With these objects in view, together with others which will appear as the description proceeds, the invention resides in the novel formation, combination and arrangement of 35 parts, all as will be described more fully hereinafter, illustrated in the drawing, and particularly pointed out in the claim.

The invention will be best understood by reference to the accompanying drawings, 40 wherein:—

Figure 1 is a front elevation of bib overalls, and illustrating the application of under garment retaining elements constructed and arranged in accordance with my invention; and

Fig. 2 is a sectional view on an enlarged scale and taken upon line 2—2 of Fig. 1.

The invention to be hereafter detailed is described as used in connection with bib 50 overalls, but it is to be understood that the device is not to be necessarily limited to use with garments of this character, but may with equal facility be employed with trousers and other outer garments, to be worn 55 by persons of either sex. In this connection, it may be also stated that the retaining or

holding elements may be used to support under garments other than drawers.

In the preferred embodiment of the invention, 4 indicates the overalls or trousers, 60 to be supported upon the human body either by suspenders or belt. The retaining elements comprise tabs or straps 5 of material preferably the same or similar to that of which the outer garment is made, the said 65 straps being secured, as by stitching, at one end to the inner face of the garment adjacent the waist portion thereof as shown. These straps or tabs may be arranged in any 70 number and spaced apart any desired distance around the waist band of the garment, and are each provided with a button hole 6 adjacent their free ends to be engaged over a button or other retaining element 7 secured to the exterior face of the garment. 75 The outer garment is provided directly above each tab 5 with an opening or slit 10, through which the free end of the adjacent tab is to pass to the exterior of the garment to be secured over the button 7. It will be 80 observed that the buttons 7 are located directly above the said openings. It will be understood that the material of which the retaining elements are formed need not be necessarily of cloth, as leather or other 85 hides, or even metallic tabs or clasps may with equal facility be used for the purpose. It will also be understood that the invention is not limited to the specific button and button hole as a fastening means for the retaining straps, as glove fasteners or other such 90 means may be used to advantage.

The under garment to be retained by the improved holding device comprises, in the present illustration, the ordinary drawer, 95 and is indicated generally, at 8. Garments of this character are usually equipped at their belt band portions or edges, with loop or strap members 9 through which suspender tabs are adapted to be inserted before being fastened to the suspender buttons to retain the garment in proper position upon the body, and the tabs or straps employed in carrying out my invention may be passed through these drawer loops before being passed through openings 10 in the outer garment and properly buttoned. It will be observed from this construction that the drawer straps will be supported by the inner portion of the retaining elements 100 adjacent the waist portion of the outer garment, and, therefore, will be hidden from 105 110

view and held against "riding up". When used for supporting drawers not equipped with such supporting bands, the under garment may be slit or apertured slightly below the upper edge thereof to permit of the insertion of the tab or strap 5. It will also be understood that other means for securing the retaining tab to the under garment may be resorted to if found more expedient. In 10 removing or detaching the under garment from the overalls or trousers band, it is but necessary to unbutton the tab or strap 5 and withdraw the said tab through the opening 10 and from engagement with the under 15 garment.

From the foregoing, it is apparent that I have provided a device which operates to prevent "riding up" of the under wear or shifting of the same sidewise about the 20 girth of the body. It will be further observed that the retaining elements or tabs will in no way detract from the general appearance of the outer garment, and may be easily and quickly unfastened when required.

25 While the above is a description of the

preferred embodiment of the invention, I am aware that various changes in the size, shape or material of which the tabs are constructed, as well as the means for retaining the tabs in fastened position, may be 30 made without departing from the spirit of the invention as defined by the claim.

What is claimed is:—

In a device of the class described, a garment, a retaining element affixed at one end 35 to the interior surface of the garment, the said garment being provided with a slit above the place of attachment of said retaining element, a button secured to said garment above said slit, and said retaining 40 element being adapted to pass through said slit and straight up to be engaged at its free end over said button.

In testimony whereof I affix my signature in presence of two witnesses.

JULIUS W. LANDQUIST.
